VINCENT FLOCCO, OF NEWARK, NEW JERSEY.

MEANS FOR CONTROLLING AND TUNING RADIO RECEIVING SETS FROM A DISTANCE.

Application filed November 25, 1925. Serial No. 71,417.

This invention relates, generally, to a novel means for controlling and tuning radio receiving sets; and the invention has reference, more particularly, to a novel 5 means for controlling and tuning radio receiving sets from any desired distance within hearing thereof.

This invention has for its principal object to provide an electrically controlled and actuated means for operating at will the rheostat, variable condensers, or similar adjustable parts of a radio receiving set from a distance, as e. g. from a distant point in the same room in which the set is located, or 10 from another room or place within listening range. The invention therefore provides a novel control for radio receiving sets which is of great general convenience, and which is of especial convenience to invalids or 15 others suffering the confinements of physical disability or illness, since it enables the latter to exercise control and effect desired adjustments of sets not within reach of their place of confinement.

20 Other objects of this invention, not at this time more particularly enumerated, will be clearly understood from the following detailed description of the same.

The invention is clearly illustrated in the 25 accompanying drawings, in which:—

Figure 1 is a face view of a radio receiving set equipped with my novel controlling means; Figure 2 is a vertical longitudinal sectional view, showing controlling means 30 and intermediate transmission for connecting the same with the elements of a radio receiving set subject to control or adjustment; Figure 3 is a side face view of a portion of the controlling means; Figure 4 is an opposite side face view of said portion 35 of the controlling means; Figure 5 is a top view of said portion of the controlling means; Figure 6 is a side elevation of said controlling means with the cover or casing 40 removed to show internal parts, and viewed as indicated by line 6—6 in Figure 45 5; Figure 7 is an end elevation of said controlling means, viewed in the direction of the arrow 7 in Figure 6; and Figure 8 is a 50 wiring diagram of the electric circuits of said controlling means.

Figure 9 is a side elevation of the hand switch device serving said controlling means; Figure 10 is a longitudinal sectional view of the same; Figure 11 is a cross section of the same, taken on line 11—11 in

Figure 9; and Figure 12 is another cross section of the same, taken on line 12—12 in Figure 9.

Figures 13, 14 and 15 are various views of a universal joint employed to couple the controlling means with transmission for connecting the same with the adjustable elements of a radio receiving set.

Similar characters of reference are employed in all of the hereinabove described views, to indicate corresponding parts.

For the purpose of illustrating the principles of construction and operation of my invention, I have shown in the accompanying drawings the application thereof to a simple radio receiving set having a front panel 20 provided with a rheostat turn-button 21, which is connected with a shaft 22 for actuating a rheostat (not shown), and further provided with adjusting or tuning dials 23 and 24 respectively connected with shafts 25 and 26 for actuating the variable condenser devices (not shown), of the receiving set. It will be understood, that by adding or duplicating the necessary parts and circuits, my controlling means may be readily adapted to serve receiving sets having a greater or less number of adjustable elements, as the case may be.

My novel selective controlling means comprises a suitable frame-work, including side plates or panels 27 and 28. Suitably supported in connection with said frame-work is an electric motor 29, to the armature shaft 30 of which is secured a worm 31, which meshes with and drives a worm-gear 32, the shaft 33 of which is journaled in suitable bearing brackets 34 connected with the motor frame. Said shaft 33 projects laterally through said side plate or panel 27, and is provided on its exterior end with a bevel gear 35. Journaled in a bearing yoke 36, which pivots on said shaft 33 intermediate the side plate or panel 27 and the bevel gear 35, is one end of a drive shaft 37, upon which is fixed a bevel gear 38 which meshes with and is driven by said bevel gear 35. The opposite end of said drive shaft 37 is journaled in a vertically movable bearing 39 which is slidable in a supporting frame 40 secured to said side plate or panel 27. Said drive shaft 37 is provided with a driver bevel gear 41. Mounted in bearing supports 42, connected with the exterior of said side plate or panel 27, is a vertically disposed jack-shaft 43, provided with a forward drive

bevel gear 44 with which said driver bevel gear 41 is normally but releasably engaged, and a reverse drive bevel gear 45 with which said driver bevel gear 41 may be selectively engaged when released from said forward drive bevel gear 44.

Journalized in and extending transversely between said side panels or plates 27 and 28, in vertically spaced apart relation, are driven shafts 46, 47 and 48, upon which are respectively fixed gear-wheels 49, 50 and 51. The outer end of the shaft 46 is connected by means of a universal joint with one end of a transmission shaft 52, the opposite end of which is connected by means of a like universal joint with a drive worm 53 which is journaled in a bearing 54 connected with the inner side or back of the front panel 20 of the receiving set. Said drive worm 53 meshes with and drives a worm gear 55 frictionally fixed on the rheostat shaft 22. The outer end of the shaft 47 is connected by means of a universal joint with one end of a transmission shaft 56, the opposite end of which is connected by means of a like universal joint with a drive worm 57 which is journaled in a bearing 58 connected with the inner side or back of the front panel 20 of the receiving set. Said drive worm 57 meshes with and drives a worm gear 59 frictionally fixed to the variable condenser tuning dial shaft 25. In like manner, the outer end of the shaft 48 is connected by means of a universal joint with one end of a transmission shaft 60, the opposite end of which is connected by means of a like universal joint with a drive worm 61 which is journaled in a bearing 61' connected with the inner side or back of the front panel 20 of the receiving set. Said drive worm 61 meshes with and drives a worm gear 62 frictionally fixed to the variable condenser tuning dial shaft 26. The above described connections are shown in Figure 2.

45 The universal joint for coupling the transmission shafts with the above described driving and driven elements comprises a tubular sleeve 63 fixed on an end of said transmission shaft so as to provide an axial receiving socket 64. The wall at the free end of said sleeve 63 is provided with a longitudinal indented slot 65. Fixed on the driving or driven member, as the case may be, is a spherical member or head 66 substantially corresponding in diameter to the internal diameter of said socket 64 of the sleeve 63, so as to be receivable therein. Connected with and projecting laterally from one side of said member or head 66 is a coupling pin 67 which, when the member or head is entered in said socket 64 is itself entered in said slot 65, all whereby rotary motion may be either transmitted to said transmission shaft or transmitted thereby as the case may be; all as will be understood

from an inspection of Figures 2 and 13 to 15 inclusive.

Fixed on the vertical jack-shaft 43 is a bevel gear 68 which meshes with and drives a bevel gear 69 on a propeller shaft 70. Said propeller shaft 70 is mounted to extend between the side plates or panels 27 and 28 in substantially parallel relation to said driven shaft 46. The outer end of said propeller shaft 70 is supported in a laterally slideable bearing 71 connected with said side plate or panel 28, and is provided with a spur gear 72 adapted at proper times to be thrown into mesh with said gear wheel 49 of the shaft 46, but which is normally maintained out of connection or mesh therewith. Connected with said side plate or panel 28 is a fulcrum piece 73, upon which is pivoted a lever 74. The lower end of said lever 74 is interconnected with said slide bearing 71 by a link 75, and its upper end is connected with a pull-string 76 which serves to hold said lever in normal position to retract said bearing 71 to thereby hold said spur gear 72 normally out of mesh with said gear wheel 49. Mounted upon a bracket member 77, or other suitable support, is an electro-magnet 78, and pivoted to said bracket member 77 in operative relation to said electro-magnet 78 is an armature-plate 79. Interconnecting the free end of said armature-plate 79 with the upper arm of said lever 74 is a link 80. When said electro-magnet 78 is energized it pulls toward it said armature-plate 79, the movement of which is transmitted through said link 80 to the lever 74, whereby the latter is turned on its fulcrum against the tension of the pull spring 76, to transmit, through the link 75, a forward sliding movement to said slide bearing 71, to thereby swing the propeller shaft 70 toward the driven shaft 46, whereby the spur gear 72 of the former is operatively engaged or meshed with the gear wheel 49 of the latter. Upon such operation the power of the motor 29 will be transmitted through the shaft 33, drive shaft 37, jack-shaft 43 and propeller shaft 70 to the driven shaft 46, which in turn will drive, through the transmission shaft 52, the above described gearing for turning the rheostat shaft 22.

Fixed on the vertical jack-shaft 43 is a bevel gear 81 which meshes with and drives a bevel gear 82 on a second propeller shaft 120 83. Said propeller shaft 83 is mounted to extend between the side plates or panels 27 and 28 in substantially parallel relation to said driven shaft 47. The outer end of said propeller shaft 83 is supported in a laterally slideable bearing 84 connected with said side plate or panel 28, and is provided with a spur gear 85 adapted at proper times to be thrown into mesh with said gear wheel 50 of the shaft 47, but which is normally main-

tained out of connection or mesh therewith. Connected with said side-plate or panel 28 is a fulcrum piece 86, upon which is pivoted a lever 87. The lower end of said lever 87 is interconnected with the slide bearing 84 by a link 88, and its upper end is connected with a pull spring 89 which serves to hold said lever in normal position to retract the bearing 84 to thereby hold said spur gear 85 normally out of mesh with said gear wheel 50. Mounted on the aforesaid bracket member 77 is a second electro-magnet 90, and pivoted to said bracket member in operative relation to said electro-magnet 90 is an armature plate 91. Interconnecting the free end of said armature plate 91 with the upper arm of said lever 87 is a link 92. When said electro-magnet 90 is energized it pulls toward it said armature plate 91, the movement of which is transmitted through said link 92 to the lever 87, whereby the latter is turned on its fulcrum against the tension of the pull spring 89, to transmit, through the link 88, a forward sliding movement to said slide bearing 84, to thereby swing the propeller shaft 83 toward the driven shaft 47, whereby the spur gear 85 of the former is operatively engaged or meshed with the gear wheel 50 of the latter. Upon such operation the power of the motor 29 will be transmitted through the shaft 33, drive shaft 37, jack-shaft 43 and propeller shaft 83 to the driven shaft 47, which in turn will drive, through the transmission shaft 56 the above described gearing for turning the variable condenser shaft 25.

Means of like construction and operation for transmitting power to produce operative relative movement of the gearing for actuating the variable condenser shaft 26 is provided in association with the driven shaft 48 and its gear wheel 51, and transmission shaft 60; said means comprising the bevel gear 93 on the jack-shaft 43 which meshes with a bevel gear 94 on a third propeller shaft 95; the slide-bearing 96 for movably supporting said propeller shaft; the spur gear 97 to mesh with the gear wheel 51 of said driven shaft 48; the lever 98 and link 99 for connecting the lower arm of said lever with said slide-bearing 96; the pull-spring 100 for retracting said lever; the electro-magnet 101 for actuating a pivoted armature plate 102; and the link 103 for operatively interconnecting said armature plate 102 with the upper arm of said lever 98.

The reference character 104 indicates a vertically disposed electro-magnet with which is associated a pivoted armature plate 105. Interconnected between the free end of said armature plate 105 and said vertically movable bearing 39 which carries one end of said drive shaft 37 is a link 106. Said armature plate 105 is normally held in

raised or retracted position by a pull-spring 107. The normally raised or retracted armature plate 105 holds said vertically movable bearing 39 in upwardly moved position, to thereby so dispose the drive shaft 37 as to normally engage its driver bevel gear 41 with the forward drive bevel gear 44 of the jack-shaft 43. Under these conditions, if any of the driven shafts 46, 47 and 48 are thrown into operation by actuation of the electro-magnetically controlled transmission mechanism above described, the operative movement transmitted thereto will be in a forward direction, to produce a forward rotation of the respective rheostat and variable condenser shafts 22, 25 and 26. If it is desired to reverse the transmitted motion, to turn back or reverse the motion of the rheostat and variable condenser shafts 22, 25 and 26, the electro-magnet 104 is energized, whereby its magnetic attraction swings downward the armature plate 105. The downward swing of said armature plate 105 draws downward the link 106, and therethrough the vertically movable bearing 39, so that the driver shaft 37 is swung downward, thus disengaging its driven bevel gear 41 from the forward drive bevel gear 44 and engaging said driver bevel gear 41 with the reverse drive bevel gear 45 of the jack-shaft 43, whereupon the movement of the transmission devices above described, when in operative relation to the jack-shaft 43, will in turn be reversed.

The means for selectively energizing the several electro-magnets above described, while at the same time cutting in and out the motor 29 will be readily understood by referring to the wiring diagram shown in Figure 8 of the drawings. Electrical energy from any suitable source may be employed, but for convenience of illustration I have shown the electrical source in the form of a battery 108. Connected with the top plate 109 of the frame-work in which the transmission mechanism is mounted is a positive pole binding post 110 and a negative pole binding post 111 respectively connected by circuit wires 112 and 113 to the respective positive and negative poles of the battery 108. Connected with said positive pole binding post 110 is a circuit wire 114 which is suitably connected with the positive pole of each electro-magnet 78, 90, 101 and 104. The negative pole of the electro-magnet 78 is connected by a conductor 115 to a binding post 116 mounted on said top plate 109. The negative pole of the electro-magnet 90 is connected by a conductor 117 to a similar binding post 118; that of the electro-magnet 101 by a conductor 119 to a similar binding post 120; and that of the electro-magnet 104 by a conductor 121 to a like binding post 122.

The manipulative switch for controlling

the circuits serving the several electro-magnets may be made in any suitable form; preferably, however, the same comprises a cylindrical tubular casing 123, within which 5 is mounted a contact carrying block 124 preferably made of a suitable insulation material, provided with stationary contacts 125, 126, 127 and 128, and corresponding movable contacts 129, 130, 131 and 132, which 10 are of resilient spring tongue type subject to actuation respectively by push-buttons 129', 130', 131' and 132' which are movably supported in and which project exteriorly through the side walls of said casing 123. 15 Extending from the binding post 116 to the stationary contact 125 is a conductor 133; and in like manner extending respectively from the binding posts 118, 120 and 122 to the respective stationary contacts 126, 127 20 and 128 are conductors 134, 135 and 136. The movable contacts 129, 130, 131 and 132 are connected in common to a return circuit wire 137 which leads to said negative pole binding post 111, and thence through the 25 wire 113 back to the battery. As will be understood the conductors 133, 134, 135, 136 and 137 may be formed as a multiple wire flexible cable C, which may be of any length desired to permit removal of said manipulative switch device to points distant from the radio receiving set per se. It will also be understood, that the cable thus formed may be arranged for detachment from the 30 radio receiving set per se by providing a multiple coupling plug P separable from a corresponding socket S, in the manner familiar to those skilled in electric wiring connections.

Suitable electric connections are also provided whereby, upon closing any electro-magnetic circuit, the motor 29 will be automatically cut in, and automatically cut out when the electro-magnetic circuit is broken. To this end the feed wire 114 is also connected to one pole of the motor 29, and the opposite pole of the motor 29 is connected by a conductor 138 with insulated stationary contact points 139, 140 and 141 respectively associated with each electro-magnet 35 device 78, 90 and 101. Mounted on the armature plate 79 so as to move therewith and electrically grounded thereon, and through the same grounded with said bracket member 77 is a contact finger 142 to 40 cooperate with the stationary contact point 139; and in like manner, the armature plate 91 of the electro-magnet 90 is provided with a contact finger 143 to cooperate with the contact point 140, and the armature plate 45 92 of the electro-magnet 101 is provided with a contact finger 144 to cooperate with the contact point 41. A conductor 145 secured to the ground provided by the bracket member 77 leads to the negative pole bind-

ing post 111, and thence through the wire 65 113 back to the battery 108.

In operation, if it is desired to manipulate the rheostat, the operator presses the button 129' of the manipulative switch, thus closing the electric circuit through the electro-magnet 78, whereupon the current flows 70 from the positive pole of the battery through the wires 112 and 114 to the magnet coils, thence through the wires 115 and 133 to the contact 125 passing through the button 75 closed contact 129 to the return wires 137 and 113 back to the negative pole of the battery. The electro-magnet 78 being thus energized, the armature plate 79 is attracted thereto, this movement throwing into operation the power transmission means actuated by the motor 29 to in turn actuate the gearing to produce forward movement of the rheostat shaft 22. At the same time the attracted movement of said armature plate 79 80 carries the contact finger 142 into circuit closing engagement with the stationary contact point 139, whereupon the circuit through the motor 29 is closed from the electrical source through the wires 112 and 114, 85 thence through the motor to the wire 138 and engaged contacts 139 and 142, thence through ground to the return wires 145 and 113 back to the electrical source. If it should be desired to reverse the movement of the 90 rheostat shaft 22, the operator, while still holding down the button 129' to close the circuit through the electro-magnet 78 and the circuit through the motor 29, also presses the button 132' of the switch device, whereupon the electro-magnet 104 is energized, to move the drive shaft 37 into reverse driving 95 relation to the jack-shaft 43 as above explained, by the closing of the circuit from the electrical source through the wires 112 100 and 114, thence through the magnet coils to the wires 121 and 136 and closed contacts 128 and 132, and thence through the return wires 137 and 113 back to the electrical source. When the push button 129' is released 105 the circuit through the electro-magnet 78 will be broken, thus permitting the retraction of the armature plate 79 to normal initial position, thereby both disconnecting the propeller shaft 70 from the driven shaft 110 46, while at the same time separating the contacts 139 and 142 to interrupt the motor circuit and stop the motor.

If it is desired to actuate the variable condenser shaft 25, the operator pushes the button 130' of the control switch device, thus closing the contacts 126 and 130 to close a circuit through the electro-magnet 90 established as follows:

Current flows from the electrical source 125 through the wires 112 and 114 to the windings of the electro-magnet 90, and thence through the wires 117 and 134 to and

through the closed contacts 126 and 130 back through the wires 137 and 113 to the electrical source. The electro-magnet 90 being thus energized, the propeller shaft 83 is thrown into gear with the driven shaft 47 so that the power of the motor may be transmitted through the already described transmission elements to the variable condenser shaft 25. At the same time, the attracted 10 movement of the armature plate 91 will engage the contact finger 143 with the contact point 140 to close the motor circuit for power production. If it is desired to reverse the driven rotation of said variable condenser shaft 25, the reverse switch button 132' is pressed to energize the magnet 104 for controlling the described reversing gear relation between the driver shaft 37 and jack shaft 43 as already above described.

20 In like manner the variable condenser shaft 26 may be actuated by pushing the button 131' of the control switch, to energize the electro-magnet 101, the current thereupon flowing from the electrical source through

25 the wires 112 and 114 to the windings of said magnet, and thence through the wires 119 and 135 to and through the closed switch contacts 127 and 131 back through the wires 137 and 113 to the electrical source; while 30 at the same time, the attracted movement of the armature plate 102 will engage the contact finger 144 with the contact point 141 to close the motor circuit. Reversing of the direction of rotation of said variable condenser shaft 26 may be accomplished in the manner already above described, by pushing the button 132' while still holding in actuated position the button 131'.

35 It will also be understood that not only are the adjustable elements of the radio receiving set subject to selective actuation through the above described control means, but any one or more or all may be simultaneously actuated in a given direction and either simultaneously or selectively stopped at any desired stage of adjustment by proper manipulation of the control buttons of the hand switch device.

40 The distance of the operator from the receiving set per se is limited only by ability to hear the results of the adjustments, since the length of the wire cable intermediate the set and the hand switch may be made to correspond to any desired conditions of use.

45 From the above description it will be apparent that my invention provides a relatively simple, yet easily manipulated adjustment control, which is efficient, and which provides the necessary flexibility and selectivity making possible delicate individual adjustment of any desired adjustable element of the receiving set.

50 I am aware that some changes may be made in the general arrangements and combinations of the various devices and parts,

as well as in the details of the construction of the same, without departing from the scope of this invention, as described in the foregoing specification, and as defined in the appended claims. Hence, I do not limit my 70 invention to the exact arrangements and combinations of the devices and parts as set forth in the foregoing specification, nor do I confine myself to the exact details of the construction of said parts as illustrated in 75 the accompanying drawings.

I claim:—

1. A remote control means for adjustable elements, comprising an electric motor, driving means actuated by said motor, driven transmission means cooperating with each adjustable element, normally disengaged means for individually coupling each driven transmission means operatively with said driving means, electro-magnetic means for actuating each coupling means, electric circuits serving said electro-magnetic means, and a portable switch device for controlling said circuits. 80

2. A remote control means for adjustable elements, comprising an electric motor, driving means actuated by said motor, means for reversing said driving means, driven transmission means cooperating with each adjustable element, normally disengaged means for individually coupling each driven transmission means operatively with said driving means, electro-magnetic means for actuating each coupling means, additional electro-magnetic means for actuating said reversing means, electric circuits serving said several electro-magnetic means, and a portable switch device for controlling said circuits. 90

3. A remote control means for adjustable elements, comprising an electric motor, driving means actuated by said motor, driven transmission means cooperating with each adjustable element, normally disengaged means for individually coupling each driven transmission means operatively with said driving means, electro-magnetic means for actuating each coupling means, a motor circuit, motor circuit make and break means actuated by each of said electro-magnetic means, electric circuits serving said electro-magnetic means, and a portable switch device for controlling said latter circuits. 100

4. A remote control means for adjustable elements, comprising an electric motor, driving means actuated by said motor, means for reversing said driving means, driven transmission means cooperating with each adjustable element, normally disengaged means for individually coupling said driven transmission means operatively with said driving means, electro-magnetic means for actuating each coupling means, a motor circuit, a motor circuit make and break means actuated by each of said electro-magnetic means, ad- 110

ditional electro-magnetic means for actuating said reversing means, electric circuits serving said several electro-magnetic means, and a portable switch device for controlling said latter circuits.

5. The combination with rotatably adjustable elements provided with power transmission means for operating the same, power driven means, normally disengaged means 10 for connecting each transmission means in driven relation to said power driven means, electro-magnetic means for selectively actuating said connecting means, and a portable switch device in circuit with said electro-magnetic means for the selective control 15 thereof.

6. The combination with rotatably adjustable elements provided with power transmission means for operating the same, power 20 driven means, normally disengaged means for connecting each transmission means in driven relation to said power driven means, electro-magnetic means for selectively actuating said connecting means, means for reversing said power driven means, electro-magnetic means for actuating said reversing means, and a portable switch device in circuit with said several electro-magnetic means for the selective control thereof.

30 7. The combination with rotatably adjustable elements provided with power transmission means for operating the same, a power driven shaft, a jack-shaft, reversible gearing intermediate said power driven shaft 35 and jack-shaft, a plurality of propeller shafts driven by said jack-shaft and corresponding to said adjustable elements of said receiving set, electrically actuated means for selectively bringing each propeller shaft into 40 driving relation to the corresponding transmission means of each adjustable element of said receiving set, electrically actuated means for bringing said power driven shaft into reverse driving relation to said jack-shaft, and a selectively manipulatable portable hand switch device in circuit with said 45 several electrically actuated means.

8. In combination with adjustable elements of a radio receiving set, an oscillatable power 50 driven shaft having a drive gear, a jack-shaft having forward and reverse gears selectively engageable by said driven shaft gear, electro-magnetic means for oscillating said drive shaft to selectively engage its 55 drive gear with said jack-shaft forward and reverse gears, a plurality of driven shafts, transmission means intermediate said driven shafts and said respective adjustable elements of said receiving set, a plurality of 60 propeller shafts corresponding to said driven shafts, drive gearing intermediate said jack-shaft and said propeller shafts, normally disengaged gearing intermediate each propeller shaft and its corresponding 65 driven shaft, electro-magnetic means corre-

sponding to each propeller shaft operative to move the latter into geared driving relation to its corresponding driven shaft, and a selectively manipulatable portable hand switch device in circuit with said several 70 electro-magnetic means for the operative control thereof.

9. In combination with adjustable elements of a radio receiving set, an electric motor, a driving shaft actuated by said motor, a jack-shaft, reversible gearing intermediate said driving shaft and said jack-shaft, electro-magnetic means for controlling the forward or reverse geared relation of 75 said driving shaft to said jack-shaft, a plurality of driven shafts respectively corresponding to the respective adjustable elements of said receiving set, transmission means intermediate each driven shaft and its corresponding adjustable element, a plurality of propeller shafts actuated by said jack-shaft, electro-magnetic means corresponding to each propeller shaft operating to move the same into and out of gear driving 80 relation to its corresponding driven shaft, a motor circuit, motor circuit make and break means actuated by each of the latter electro-magnetic means, electric circuits serving all of the aforesaid electro-magnetic 85 means, and a portable switch device having selectively manipulatable make and break means corresponding to each electro-magnetic circuit.

10. In combination with adjustable elements provided with power transmission 100 means for operating the same, power driven means, normally disengaged means for connecting each transmission means in driven relation to said power driven means, electro-magnetic means for selectively actuating 105 said connecting means, electric circuits serving said electro-magnetic means, and a portable switch device having selectively manipulatable make and break means corresponding to each electro-magnetic circuit.

11. In combination with adjustable elements provided with power transmission 110 means for operating the same, power driven means, normally disengaged means for connecting each transmission means in driven relation to said power driven means, electro-magnetic means, for selectively actuating 115 said connecting means, means for reversing said power driven means, electro-magnetic means for actuating said reversing means, electric circuits serving said several electro-magnetic means, and a portable switch device having selectively manipulatable make 120 and break means corresponding to each electro-magnetic circuit.

12. In combination with adjustable elements, an electric motor, driving means actuated by said motor, means for reversing 125 said driving means, driven transmission means cooperating with each adjustable ele-

ment, normally disengaged means for individually coupling said driven transmission means operatively with said driving means, electro-magnetic means for actuating each coupling means, a motor circuit, motor circuit make and break means actuated by each of said electro-magnetic means, additional electro-magnetic means for actuating said reversing means, electric circuits serving

said several electro-magnetic means, and a portable switch device having selectively manipulatable make and break means corresponding to each electro-magnetic circuit.

In testimony, that I claim the invention set forth above I have hereunto set my hand this 17th day of November, 1925.

VINCENT FLOCCO.
